UNITED STATES PATENT OFFICE.

EUGENE KIES, OF CHICAGO, ILLINOIS.

LOCK.

1,217,012.

Specification of Letters Patent.

Patented Feb. 20, 1917.

Application filed February 20, 1915. Serial No. 9,723.

To all whom it may concern:

Be it known that I, EUGENE KIES, a citizen of the United States, residing at Chicago, in the county of Cook and State of Illinois, have invented certain new and useful Improvements in Locks; and I do hereby declare the following to be a full, clear, and exact description of the invention, such as will enable others skilled in the art to 10 which it appertains to make and use the same.

This invention relates to new and useful improvements in locks and the principal object of the device is to provide a lock wherein the necessity of providing a key is eliminated.

Still another object of the invention is to provide a lock which cannot be opened except by the persons knowing the proper combination.

Still another object of the invention is to provide a lock having a plurality of movable stops which are adapted to be adjusted to form various combinations and in which 25 it is possible for the user to readily change the combination, thus avoiding any possibility of persons becoming familiar with the single combination.

Still another object of the invention is to 30 provide a lock wherein the possibility of changing the combination unless the lock is opened is eliminated.

A further object of the invention is to 35 provide a device which is readily applicable to padlocks, door locks or any other type of lock.

With these and other objects in view, the invention consists in the novel combination and arrangement of parts which will be 40 fully set forth in the following specification and accompanying drawings, in which:—

Figure 1 is a side view in elevation of a lock constructed in accordance with this invention.

Fig. 2 is an end view thereof.

Fig. 3 is a vertical sectional view through the lock illustrating one side thereof and showing the interior mechanism.

Fig. 4 is a view similar to Fig. 3 on the 50 opposite side of the lock, showing the latch removed.

Fig. 5 is a vertical sectional view on the line 5—5 of Fig. 3.

Fig. 6 is a detail perspective view of a

fragment of the lock illustrating the latch mechanism.

Fig. 7 is an enlarged detail end elevation of the block adjuster illustrating the gear controlling the same.

Fig. 8 is a detail perspective view of one 60 of the stop blocks of a modified form.

Fig. 9 is a sectional view on an enlarged scale on line 9—9 of Fig. 3.

Fig. 10 is a detail perspective view of the stop carriage illustrating a method of bracing the same if so desired.

Fig. 11 is a vertical sectional view through a padlock constructed in accordance with this invention.

Fig. 12 is a side elevation of a modified 70 form of stop carriage for use in connection with the lock, and

Fig. 13 is a top plan view of a portion of the stop block holder.

Referring to the drawings, the numeral 1 75 designates the casing of the device comprising the main compartment 2 and the extension 3. The outer wall 4 of the casing is provided with the lock bolt opening 5, the latch opening 6, the stop block adjusting 80 bar opening 7 and the opening 8 through which the stop block carrier is adapted to be removed for changing the combination. The sides of the casing are provided with aligned openings through which the shaft 8' 85 for the latch extends and this shaft 8' is provided at its outer end with the usual knobs 9 for controlling the movement of the latch. A similar pair of aligned openings is formed near the lower end of the chamber or body 90 2 and are adapted to receive the shaft 10 which controls the operation of the lock and carries at its outer ends the knobs 11 by which the same is turned.

Formed within the casing is a suitable 95 supporting wall 12 for the stop block carrier and immediately above the wall 12 is a supporting wall 13 for the lock bolt and the lock block. A suitable wall 14 is formed at a point above the wall 13 and is adapted 100 to form a guide for the receipt of the lock bolt. Extending upwardly in close proximity to the front wall 4 of the casing and between the wall 14 and the upper wall thereof is a vertical wall 15 provided with an aperture 16 alining with the aperture 6 for the reception of the latch. A suitable wall 17 extends upwardly from the bottom of the

casing to a point slightly below the opening 7 and has attached thereto the block 18 provided with the reduced extension 19 having the opening 20 through which the adjusting bar for the stop block is slidable.

Slidable through the opening 6 in the wall 4 and through the opening 16 in the wall 15 is the latch 21 provided with the bevel face 22 and formed integrally with the latch and 10 extending inwardly therefrom is the extension 23 which is slidable between the fingers 24 formed integrally with one of the side walls of the casing 2. This extension is provided with the notches 25 and seated in 15 the notches are the inward ends of the fingers 26 formed at the ends of the arms 27 of the latch operating member 28 which is formed with the outer extension 29 projecting from one of the side faces of the arms 20 27 as clearly shown in the drawings. This latch operating member is adapted to be engaged by the oppositely extending arms 30 which are secured to the shaft 8' and carried on a suitable sleeve 31 as clearly shown 25 in Fig. 3.

Slidable through the opening 5 in the wall 4 and resting on the wall 13 is the lock bolt 32 provided with the reduced extension 33 which is formed with a series of stops or 30 shoulders 34 against which the lock block 35 abuts. This lock block is provided with a plurality of shoulders which conform to the shape of the shoulder 34 and the rear end of the block engages the rear wall of the 35 chamber 2 of the lock casing 1. As illustrated in Fig. 9 it will be noted that the lock block is of greater width than the bolt and is so constructed as to be engaged by the stop block carriage upon its upward movement so that the block will be lifted thereby permitting the shoulders to disengage. The bolt is formed with a finger 36 which extends outwardly from one side thereof and is adapted to engage the walls of the tapered 45 groove formed in the stop block carriage as will be more fully hereinafter described. The opposite side of the bolt is provided with the downwardly extending rack bar 38 provided on its under side with teeth for engagement with the bolt actuating gear which will be more fully hereinafter described.

The stop carrier is designated generally by the numeral 39 and consists of the rear 55 wall 40 provided with a plurality of forwardly extending partition walls 41. This rear wall is formed with a plurality of vertically extending slots 42 formed centrally of the walls 41 and these slots are adapted 60 to receive the blocking arms of the stop blocks which will be more fully hereinafter described. The forward end wall of the stop block carrier 39 is provided with a suitable knob 43 and the whole carrier is 65 made of a size to readily slide through the

opening 8 provided in the front wall therefor.

The stop blocks used in connection with the device are best illustrated in Fig. 8 and each comprises an oval body 44 provided at 70 its rear face with a groove 45 and centrally with a stem 46 provided at its extreme rear end with the locking arm 47. It is to be understood that this body may be made oval as illustrated in Fig. 8 or may be made circular as illustrated in Fig. 11 without departing from the spirit and scope of the invention.

The stop block carriage used in connection with the device is best illustrated in Fig. 10, 80 though in this form it will be noted that the reinforcing arms are shown but it is to be understood that these arms may be eliminated at the desire of the user. This stop block carriage comprises a strip of metal 48 85 formed with a central slot 49 extending longitudinally thereof which is provided at its forward end with the offset portion 50. The rear end of the strip has formed integral therewith the outstanding wall 51 90

which engages the side walls of the casing 1 and forms a guide for the rear end of the stop block carriage. A longitudinally extending tongue 52 is formed to one side of the slot 49 and is adapted to form a guide to prevent the stop blocks from turning when inserted in place in the carriage. At the forward end of the body 48 is a depending standard 53 provided at its lower end with a pair of vertically extending parallel 100 guides 54 which straddle the wall 17 and form a guide for the lower end of the device. Formed near the lower end of the standard 53 and extending in a direction parallel to the strip 48 are the teeth 55 which are adapted to be engaged by the tooth on the controlling wheel as will be more fully hereinafter described. In order to hold the two portions of the strip in parallel relation, there are provided the connecting 110 members 56 which are provided at spaced intervals and hold the said portions formed by the slots 49 in spaced parallel relation at all times. These connecting members are bowed outwardly as illustrated in Fig. 5 so 115 as to avoid interference with the retaining arms 47 of the stop blocks 44. A suitable tapered groove 57 is formed at the forward end of the upper arm of the carriage and this groove is adapted to receive the finger 120 36 of the lock bolt 32 upon rearward movement of said lock bolt. The slot 49 is of a width sufficient to receive the stems 46 of the stop blocks 44 so that the blocks may be slid longitudinally of the stop block carriage to align with the spaces left upon their removal from the carrier 39.

The adjustability of the stop blocks is effected by the stop block adjuster consisting of a rack bar 58 which is segmental in cross 130

section as illustrated in Fig. 7 and is slidable through a segmental opening 59 formed in the gear wheel 60 which gear wheel meshes with the gear teeth on the rack bar 61 which is slidable transversely through the lock. The outer ends of this rack bar 61 are provided with suitable knobs 62 by which its movement may be controlled. The segmental rack bar 58 is provided intermediate 10 its ends with an upstanding lug 63 provided with oppositely disposed curved faces for engaging the stop blocks so that upon inward or outward movement of the rack bar 58 the stop blocks may be slid longitudinally 15 of the stop block carriage. In order that the lug 63 may pass by one or more of the stop blocks without moving the same the rack bar 61 is moved to cause the rack bar 58 to partly rotate so as to swing the lug 20 downwardly into a horizontal position and thus the rack bar 58 and lug 63 will be free to move without disturbing any of the blocks. This wheel 60 is formed with a sleeve 64 which is rotatable in the aperture 25 20 of the extension 19 of the block 18.

In order to move the rack bar 58 longitudinally there is provided the gear 65 which is secured to the shaft 66 and meshes with the teeth of the rack bar. A suitable pinion 30 67' is mounted on the shaft 66 and this pinion in turn meshes with the gear wheel 67 on the shaft 68 which gear wheel 67 meshes with the gear wheel 69 which is attached to the shaft 10. It will thus be seen that upon 35 rotation of either of the knobs 11 the rack bar 58 may be moved longitudinally so as to adjust the stop blocks 44 along the carriage. The shaft 66 is extended beyond the sides of the casing and has mounted thereon the dial 40 wheel 70 provided with a plurality of characters 71 around its periphery which are visible through suitable openings formed in the escutcheon plates, and the edge of this wheel is provided with a plurality of out- 45 standing teeth or lugs 73 which engage the offset portion 74 of the spring tongue 75 which in turn is mounted on a suitable block 76 secured to one of the walls of the casing. The lugs 73 are positioned in radial alignment 50 with the characters 71 and it will thus be seen that as the characters appear before the opening in said escutcheon plates, the tongue 75 will ratchet over the lugs and serve to hold the dial wheel against accidental movement. 55

Keyed to the shaft 10 is a sleeve 77 carrying the arms 78 which engage the springs 79 mounted on the ears 80 of the wheel 81. This wheel 81 is provided with the radial 60 arm 82 carrying a tooth 83 for engaging the teeth 55 of the standard 53. It will thus be seen that upon rotation of the shaft 10 the arms 78 will engage the springs 79 and thus cause the wheel or disk 81 to revolve but it 65 will be apparent that unless the stop block

carriage moves upwardly freely the tooth 83 engages the teeth 55 and will stop the rotation of the disk and the springs 79 will give to allow the arms 78 to pass. In this way it will be apparent that unless the proper combination is set up within the lock the same cannot be forced. A similar construction is provided for driving the gear train controlling the rearward movement of the bolt which train will be described as follows: 70 75

Mounted to rotate freely on the shaft 10 is the gear 84 carrying the outstanding ears 85' which in turn support the springs 86'. These springs 86' are arranged to be engaged by the arms 87' of the sleeve 88' 80 which is keyed or otherwise secured to the shaft 10 and the gear 84 meshes with a pinion 85 mounted on the stub shaft 86 and this pinion meshes with the gear 87 mounted on the stub shaft 88 which gear in turn meshes with the rack 38 so as to operate the bolts. It will thus be seen that unless the lock block 35 is raised the bolt cannot be forced backwardly as the spring 86 will give and permit the arms 87 to pass but it 85 will also be noted that the springs will offer sufficient resistance to operate the bolt provided the block 35 is raised. It is to be noted that the lock block is provided with a dove-tail groove 89 for the reception of the dove-tail rib 90 formed on one of the side walls of the chamber 2. It will thus be seen that the block will be free to move in a vertical plane but will be held against accidental movement in other directions. 90 95 100

Referring to Fig. 11 in which there is illustrated a padlock, it will be seen that the lock casing is designated by the character 91 forming a chamber 92. Formed integrally with the inner face of one of the walls of the casing are the inwardly extending guide tongues 93 which act as guides for the latch, which will be more fully hereinafter described. 105

The latch above referred to is designated by the numeral 94 and is provided with the beveled end 95 and said latch is adapted to engage the notched end of the shackle 96 which is pivoted as at 97 to the lock. The lower end of the shackle is provided with the curved end 98 which is adapted to engage the bevel face 95 of the latch to force the same backwardly against the compression of the spring 99. Suitable guide walls 100 are formed integrally with the back wall of the casing and serve as guides which coöperate with the tongues 93 and also form stops against which the lugs 101 on the latch abut when said latch is moved forwardly and in engagement with the shackle. It will thus 110 be seen that the forward movement of the latch is limited so that when the shackle is removed the same cannot move beyond a predetermined distance. Formed integrally with the rear end of the latch is an exten- 115 120 125 130

sion 102 formed with the downturned arm 103, the lower end of which is formed with the forwardly turned lug 104 and this arm 103 forms the hook against which the end of 5 the lever 105 operates when moving the latch to its open position. This lever 105 is carried on a suitable sleeve 106 which is pivoted as shown in the drawing and is formed with an arm 107 provided with the enlargement 108 which is adapted to be engaged by the stop block carriage when the same is moved upwardly.

The carriage above referred to is designated generally by the numeral 109 and is 15 constructed identically with the carriage 48 and is slideable vertically within the lock casing. The stop carrier designated by the numeral 110 is constructed identically with the stop carrier 39 and the stops 111 are 20 constructed and operate the same as do the stops 44 hereinbefore referred to. The forward end of the lock casing 91 is provided with an opening 112 through which the stop carrier may be withdrawn to vary the combination and this opening is closed by a suitable plate 113, the upper end of which is formed with the angular extension 114 which is engaged by the end of the shackle when the same is in locked position. It will thus 25 be seen that the removal of the plate unless the lock is in open position is prevented.

The stops 111 are adjusted along the carriage 109 by a rack bar 115 which is identical in construction with the rack bar 38 and 35 is controlled by the gear 116 which is rotated by the rack bar 117. The rack bar 115 is moved longitudinally by a mechanism which will be more fully hereinafter described.

The mechanism above referred to 40 comprises the disk 118 provided with a plurality of teeth on its periphery which engage the teeth of the rack bar 115 and this disk 118 is provided with the characters 119 which are visible through a suitable opening formed in 45 the casing 91. This disk is secured to the shaft 120 and rotatably mounted on said shaft is the disk 121 carrying the angular extension 122 provided with a tooth 123 for engaging the teeth 124 on the standard of 50 the carriage 109. The connection between the disk 118 and the disk 121 is of the same construction as the connection between the disk or wheel 69 and the disk 81. It will thus be seen that any attempt to force the 55 lock will be frustrated.

In the modified form of the stop block carriage illustrated in Fig. 12, it will be noted that the forward end of said carriage is provided with an enlargement 122' 60 provided with an opening 123' and is adapted to be pivoted to the casing. The standard designated by the numeral 124' is curved and provided on its inner face with the teeth 125' for engagement with the tooth on either 65 the extension 82 or 122. In this modified

form it will be noted that the carriage instead of moving straight upwardly as in the previous construction will swing on the pivot which extends through the opening 123' and will engage the various lock releasing means, 70 thus permitting the door or padlock to be opened.

It will be apparent from the foregoing that in use the combination is set by removing the stop carrier 39 and removing certain 75 of the stop blocks 44 and placing the same in the carriage. The carrier is then replaced into the position shown in the drawing and the lock is ready for operation. The user first turns the bar 58 into such a position 80 that the arm 63 at its end extends upwardly to engage the stop blocks 44 and upon revolving either of the knobs 11 it will be apparent that the gear train controlling the movement of the bar 58 will move said bar 85 so as to slide the first of the stop blocks to the proper position. The bar is then turned by the operation of the rod 61 so that the arm or finger 63 turns downwardly and escape beneath the stop blocks and upon 90 turning the same upwardly it will be apparent that the next block may be set to the proper position. This operation is repeated until the blocks are alined with the openings 95 left for them by their removal from the carrier 39 and the bar 58 is then moved entirely back into the lock whereupon the user upon turning the arm will operate the gear train to swing the extension 82 around so that the tooth 83 engages the teeth 55 of the 100 standard 53.

The engagement of the tooth 83 with the lowermost tooth 55 will move the standard upwardly, thus lifting the carriage until the same engages the under side of the lock block 105 35 and upon further rotation of the gear train it will be apparent that the bolt actuating gear train will be set in motion to slide the bolt backwardly and out of locking position. The carriage is held against falling back to its locked position by the finger 110 36 which engages the upper inclined wall of the groove 57 and it will be apparent that the farther into the casing the lock bolt is moved the higher the carriage will be raised, 115 thus lifting the lock block 35 clear of the bolt and permitting the same to be entirely withdrawn from locking position. In this way it will be apparent that the lock may be thrown to open position and may again 120 be locked by reversing the direction of rotation of the knob to return the parts to their original positions whereupon the bar 58 is thrown into such a position that the lug 63 extends upwardly and engages the blocks 44 125 of the carriage to assist the same to their original or starting position. Due to the fact that any of the blocks may be removed and placed in the carriage it will be apparent 130 that the combination may be readily

changed and the lock cannot be opened by any person unless they are familiar with the combination.

The operation of the padlock structure is similar to that of the door lock excepting that in place of the carriage engaging the lock block 35, the carriage 109 engages the extension 108 thereby rocking the lever 105 and causing the same to force the arm 103 rearwardly to move the latch 94 out of engagement with the shackle thereby permitting said shackle to be readily opened.

While in the foregoing there has been shown and described the preferred embodiment of this invention, it is to be understood that such changes may be made in the combination and arrangement of parts as will fall within the spirit and scope of the appended claims.

20 What is claimed is:-

1. In a lock of the class described, a lock bolt, a lock block for holding said bolt against inward movement, a carriage for lifting said block out of engagement with the bolt, movable stop blocks carried by the carriage, means to move the stop blocks and stop blocks stationary within the lock to prevent the carriage from being moved unless the movable stop blocks are properly set.

30 2. In a combination lock, a lock bolt, a lock block for holding the bolt in locked position, a carriage for moving said lock block out of engagement with the bolt to permit the bolt to be operated, a plurality of movable stop blocks carried by the carriage and adjustable longitudinally thereof, a stop block carrier and a plurality of stationary stop blocks carried by said carrier and adapted to engage the movable stop blocks 40 to prevent the movement of the carriage unless the proper combination is set up.

35 3. In a combination lock, a lock bolt, a lock block, for holding the bolt in locked position, a carriage for moving the block out of engagement with the bolt, movable stop blocks carried by the carriage, a carrier slideable in the lock, stop blocks carried by the carrier, the movable stop blocks in the carriage being removed from the carrier and placed in the carriage, thus leaving blank 50 spaces in the carrier and means to adjust the stop blocks carried by the carriage to align with the blank spaces in the carrier whereby the carriage may be moved upwardly to release the bolt.

45 4. In a combination lock, a lock bolt, a lock block holding the bolt in locked position, a carriage for moving the block, combination means to lock the carriage, a gear 60 train to move the carriage when the proper combination is set up, and a second gear train to move the bolt.

50 5. In a combination lock, a lock bolt, a lock block holding the bolt in locked position, a plurality of relatively stationary stop

blocks within the lock, a carriage adapted to engage the lock block to move said block out of engagement with the bolt, stop blocks carried by the carriage and adapted to engage the relatively stationary stop blocks unless 70 moved to the proper combination and a gear train for controlling the setting up of the combination and a second gear train controlling the movement of the bolt.

6. In a combination lock, a movable carriage, a stop block carrier, stop blocks adapted to be removed from the carrier and slidably mounted on the carriage, said stop blocks adapted to pass the carrier through the spaces left by their removal, means to 80 adjust the stop blocks longitudinally of the carriage and a lock releasing mechanism actuated upon engagement with the carriage.

7. In a combination lock, a casing, a stop block carrier within the casing, stop blocks 85 in the carrier, a carriage adapted to slide past the carrier, some of the stop blocks in the carriage being removed from the carrier and mounted on the carriage, means to adjust these stop blocks longitudinally of the 90 carriage and lock released means adapted to be engaged by the carriage to permit the lock to be opened.

8. In a combination lock, a lock bolt, a locking means for said bolt, a stop block 95 carriage for moving the bolt locking means into bolt releasing position, a stop block carrier, stop blocks carried thereby, some of the stop blocks being removed and placed in the carriage, means to adjust the stop blocks longitudinally of the carriage, a gear train controlling the movements of the stop block adjusting means, a dial to indicate when the proper combination is set up and a gear train for moving the carriage and thereby releasing the locking means.

9. In a combination lock, a stop block carrier, a lock releasing means, a carriage, stop blocks carried by the carriage and by the stop block carrier, the carriage being adapted to engage and release the lock releasing means, a segmental rack bar movable longitudinally of the carriage, a lug carried by said rack bar for engaging the stop blocks in the carriage whereby the said stop blocks 110 may be moved longitudinally of said carriage, means to throw the lug into inoperative position, a gear train meshing with the rack bar for controlling its longitudinal movement, a dial wheel in the gear train to 115 indicate the proper combination and means to indicate when the indications on the dial wheel pass a predetermined point.

10. In a combination lock, a lock bolt, a stop block carrier, stop blocks carried by 125 said carrier, a bolt releasing means, a stop block carriage adapted to slide past the carrier to engage the bolt releasing means, stop blocks adjustably mounted on the carriage, means to adjust said stop blocks on the car- 130

- riage to aline the same in such a position that they will pass the carrier and means for moving the carriage against the bolt releasing means to release said bolt.
11. In a combination lock, a housing, a bolt slideable within the housing, a bolt releasing means for moving said bolt into releasing position, a stop block carrier removably mounted within the housing, a stop block carriage adapted to slide past the stop block carrier, stop blocks mounted in the carrier certain of said stop blocks being mounted in the carriage and adjustably connected thereto, adjusting means for moving said stop blocks and means for lifting the carriage against the bolt releasing means when the proper combination is set up.
12. In a combination lock, a lock bolt, a lock block holding said bolt in locked position, a plurality of abutting shoulders on the lock bolt and lock block, means to raise the lock block to disengage the shoulders and allow a step by step releasing of the bolt and means carried by the bolt to engage and hold the block lifting means.
13. In a combination lock, a lock bolt, a lock block holding said bolt in locked position, a plurality of abutting shoulders on said lock bolt, and lock block means to initially raise the stop block to disengage the shoulders and allow the bolt to be partially withdrawn and means carried by the bolt to hold the block raising means to prevent the same from falling.
14. In a combination lock, a lock bolt, a lock block mounted in the rear of said bolt and in abutting engagement therewith when said bolt is in projected position, the block being of greater width than the bolt, and overhanging one side of the bolt, means connected to the opposite side of the bolt to operate the same, means to engage the overhanging portion of the block to move the same out of engagement with the bolt and means actuated by the bolt operating means to raise the block engaging means.
15. In a combination lock, a lock bolt, a lock block in abutting engagement with the lock bolt when the device is in locked position, means to move said block out of engagement with the bolt, stop blocks adjustably carried by the block engaging means, stop blocks for coöperation with the first named stop blocks, a segmental rack bar having its teeth formed on its curved face, a finger carried by the rack bar for engaging and adjusting the adjustable stop blocks, a gear train for controlling the longitudinal movement of said rack bar and the block raising means, a gear train for withdrawing the bolt, and means to rotate the segmental rack bar to throw the finger into operative and inoperative position.

EUGENE KIES.
